ANTIRECOIL DEVICE FOR FIREARMS

Russell M. Catron, New Haven, Conn., assignor to
Western Cartridge Company, New Haven,
Conn., a corporation of Delaware

Application December 9, 1942, Serial No. 468,331

9 Claims. (Cl. 89—14)

The present invention relates to improvements in anti-recoil devices for firearms, that is to say, devices which serve to effect a diminution in the recoil shock of shotguns, rifles, and other firearms, when the same are discharged.

One of the objects of the present invention is to provide a superior device or construction whereby the recoil shocks of firearms are materially lessened to thereby minimize physical discomfort to the marksman, as well as to enable the marksman to more nearly maintain the firearm directed at the chosen target following each discharge thereof.

Another object of the present invention is to provide a superior anti-recoil device suitable for use on automatic firearms of the recoiling-barrel type and serving, when incorporated in such a firearm, to minimize the battering of the firearm-structure as a result of the rearward travel of the recoiling-barrel when the firearm is discharged.

A further object of the present invention is to provide a superior anti-recoil device for firearms which, in addition to discharging a function of minimizing recoil, also discharges a function of improving the shot pattern in instances where shot shells are discharged.

Still another object of the present invention is to provide a superior anti-recoil device for shot-guns so constructed and arranged as to minimize the chances of the wadding usually employed in shot shells from breaking through the mass of shot to thereby cause an uneven and unsatisfactory distribution of the said shot on the target.

A still further object of the present invention is to provide a superior firearm construction embodying anti-recoil means of a superior character which, despite its serving to minimize recoil, will accomplish such result without harmfully lessening the effective muzzle-velocity of the shot or projectile.

Another object of the present invention is to provide a superior anti-recoil device suitable for use on shotguns and by means of which not only is the shock of recoil minimized but the marksman may readily and conveniently select any one of a given variety of choke effects for use in conjunction with shot shells.

A further object of the present invention is to provide a superior anti-recoil firearm construction whereby the recoil effects may be materially lessened without, however, causing wadding or portions of the shot charge from being uselessly or harmfully dispersed laterally.

With the above and other objects in view, as

will appear to those skilled in the art from the present disclosure, this invention includes all features in the said disclosure which are novel over the prior art.

5 In the accompanying drawings, in which certain modes of carrying out the present invention are shown for illustrative purposes:

Fig. 1 is a broken view in side elevation of a recoiling-barrel shotgun equipped with an anti-recoil device constructed in accordance with the present invention;

Fig. 2 is a view in central-longitudinal section of one form of anti-recoil device constructed in accordance with the present invention, together with the forward portion of a shotgun-barrel to which the device is applied, the supplemental barrel-member of the device being shown in its normal rearward position;

Fig. 3 is a view similar to Fig. 2 but showing 20 the supplemental barrel-member in its forward position and schematically showing in the said barrel-member a shot-charge together with the accompanying shot-shell wadding;

Fig. 4 is a transverse sectional view taken on 25 the line 4—4 of Fig. 2;

Fig. 5 is a similar view taken on the line 5—5 of Fig. 3;

Fig. 6 is a view in side elevation of the body-member, detached;

Fig. 7 is a view thereof in rear-end elevation;

Fig. 8 is a view thereof in front-end elevation;

Fig. 9 is a view thereof in central-longitudinal section;

Fig. 10 is a view in side elevation of the supplemental barrel-member;

Fig. 11 is a rear-end view of the supplemental barrel-member;

Fig. 12 is a front-end view of the supplemental barrel-member;

Fig. 13 is a view thereof in central-longitudinal section;

Fig. 14 is a broken view in side elevation of the forward end of the main barrel; and

Fig. 15 is a front-end elevation thereof.

The particular firearm selected for illustration in the accompanying drawings to make clear one embodiment of the present invention, includes a buttstock 15 supporting a frame or receiver 16 from which latter forwardly extends a barrel 17 attached at its rear to the frame 16, and extending forwardly therefrom beneath the barrel 17 is a forestock 15a. In the particular instance shown, the shotgun is of the recoiling-barrel type, that is to say, a shotgun in which the barrel 17

or its equivalent slides rearwardly into the frame 16 when the firearm is discharged. The forward portion of the barrel 17 has its wall outwardly thickened and a short distance rearwardly of its forward end, the said barrel is formed with an annular rib or shoulder 18 forwardly of which the said barrel is formed with external threads 19. The extreme forward end of the said barrel 17 is provided with an outwardly - and - rearwardly - sloping conically - contoured face 20, for purposes as will hereinafter appear.

Fitting over the threaded forward portion of the barrel 17 is the rear portion of a tubular body-member or housing generally designated by the reference character 21, and having its rear edge normally firmly seated against the forward face of the annular rib or shoulder 18 on the barrel 17. Within its rear portion, the said body-member is formed with threads 22 interfitting with the threads 19 on the barrel 17 to firmly hold the said body-member 21 in coaxial assembled relationship with respect to the barrel 17. Adjacent its rear end, the body-member 21 is formed with an annular series of gas-vent ports 23 leading outwardly and rearwardly from the bore 24 of the said body-member to the outer periphery of the rear portion of the body-member 21.

Adjacent its forward end, the body-member 21 is provided with a concentric annular stop-lip 25 projecting inwardly and rearwardly and terminating in a conically-contoured annular stop-face 26. The said stop-face 26 slopes rearwardly and outwardly from the mouth-opening 27 located at the forward end of the body-member 21 and surrounded by the stop-lip 25 before referred to. The said mouth-opening 27 is concentric with the bore 24 of the body-member 21 and hence also concentric with respect to the bore 28 of the barrel 17. Externally, the forward portion of the body-member 21 is formed with a hexagonal wrench-receiving portion 29 by means of which the rear end of the said body-member may be firmly seated against the forward face of the rib or shoulder 18 on the barrel 17.

Within the forward end of the body-member 21 and surrounding the rear portion of the stop-lip 25 therein is an annular groove 30 having a forward wall of semicircular form in cross section and adapted to provide a seat for a return-spring in a manner as will be hereinafter described. The said body-member 21 is also formed adjacent its forward end with a plurality of air-vent ports 31 serving purposes as will also be hereinafter described.

Located within the body-member 21 with capacity for axial reciprocation is a tubular member generally designated by the reference character 32 and which for reasons as will hereinafter appear, acts in effect as a supplemental barrel-member and will, therefore, be hereinafter referred to as such. The said supplemental barrel-member is formed at its rear end with an annular radially-projecting flange or rib 33 having a smooth sliding fit in the bore 24 of the body-member 21. Adjacent its forward end, the supplemental barrel-member 32 is formed with an annular flange or rib 34 also having smooth sliding bearing in the bore 24 of the body-member 21. The said supplemental barrel-member 32 has an axial bore 35 which is in axial alignment with the bore 28 of the barrel 17 so as to virtually constitute a continuation thereof. The rear end

of the supplemental barrel-member 32 has a conically-contoured rear face 36 conforming to and normally seated against the conically-contoured forward face 20 of the barrel 17. At its extreme forward end, the barrel-member 32 is provided with a conically-contoured stop-face 37 which conforms to and is adapted to engage with the conically-contoured stop-face 26 within the forward end of the body-member 21, under circumstances as will hereinafter appear.

Interposed between the forward face of the annular flange or rib 34 adjacent the forward end of the supplemental barrel-member 32 and the forward wall of the groove 30 within the forward end of the body-member 21, is a helical return-spring 38. The said return-spring 38 normally yieldingly maintains the supplemental barrel-member 32 in its rearward position in which the face 36 at the rear end of the said barrel-member is seated against the face 26 at the forward end of the barrel 28.

Operation

Let it be assumed for purposes of description that the parts are in their normal positions, as is especially well shown in Fig. 2.

Now when the firearm is discharged, the shot-charge, together with the wadding (such, for instance, as the shot-charge 39, the rear wadding 40 and front wadding 41), will be propelled forwardly through the bore 28 of the barrel 17 and will enter the bore 35 of the supplemental barrel-member 32. Now with a sufficiently-strong spring, such as the return-spring 38, the shot-charge, together with the wadding, will completely enter the bore 35 of the supplemental barrel-member 32 before sufficient friction is created to cause the said supplemental barrel-member to move forwardly to disengage its conically-contoured rear-face 36 from the similarly-contoured forward-face 26 of the barrel 17.

Ultimately and before the shot-charge and wadding will pass forwardly completely out of the structure, the supplemental barrel-member 32 will be moved forwardly against the tension of the return-spring 38 until the stop-face 37 of the said barrel-member engages with the stop-face 26 within the forward end of the body-member 21. The parts will now have assumed substantially the positions in which they are shown in Fig. 3.

Substantially as soon as the supplemental barrel-member 32 moves forwardly, as above described, under the urge of the shot-charge and wadding, the annular flange or rib 33 at the rear of the said barrel-member, will start to uncover the gas-vent ports 23 in the rear portion of the body-member 21, and when the parts reach the positions in which they are shown in Fig. 3, the said gas-vent ports will be fully uncovered. As soon as the gas-vent ports 23 are uncovered, as just described, gas under pressure will escape through the said ports in an outwardly - and - rearwardly - inclined direction to thereby materially counter the recoil effects of the discharge. The recoil effects will also be further countered by the forward pressure exerted on the return-spring 38 and hence on the body-member 21, and by the striking of the supplemental barrel-member 32 against the stop-face 26 within the forward end of the said body-member.

In instances where the return-spring 38 or its equivalent has sufficient tension, as is preferred, to maintain the rear end of the supplemental

barrel-member 32 against the forward end of the barrel 17 until the shot-charge and wadding 39, 40 and 41 have fully cleared the forward end of the barrel 17, naught but gases and gas residue will pass outwardly through the gas-vent ports 23 or their equivalent. In instances where the timing is not as just described, fragments of wadding and in some instances small shot might be blown outwardly through the gas-vent ports 23.

As the shot-charge 39 and the wadding 40 and 41 emerge from the forward end of the barrel 17, they will have substantially their maximum velocity in most instances. Under these conditions and due to the opening of the gas-vent ports 23, the shot-charge 39 when it emerges from the mouth-opening 27 of the body-member 21 will not have the relatively-light and therefore readily-acceleratable rear wadding 40 blown through the shot-charge to thereby disrupt the same and cause a large blank space in the shot pattern when the shot reaches the target-area.

The bore 35 of the supplemental barrel-member 32 shown in the accompanying drawings, tapers inwardly from its rear to about the point 42 on an arc of about 17-foot radius to thereby produce what might be termed a "full choke" bore. From the junction-point 42 forwardly, the bore 35 is of cylindrical form.

Should the user of the firearm desire to employ a modified choke or no choke at all, in lieu of that provided in the bore 35 of the supplemental barrel-member 32, a different supplemental barrel-member may be substituted for that shown. Such a substitute supplemental barrel-member should in general correspond to the supplemental barrel-member 32 save that its bore, corresponding to the bore 35, would be modified to meet the specific choke or no-choke action desired by the marksman.

When the supplemental barrel-member 32 moves forwardly as has been previously described, air and such powder residue as might be located in the forward end of the body-member 21 will be forced outwardly through the air-vent ports 31 in the said body-member.

It is also to be noted that when the conically-contoured stop-face 37 of the supplemental barrel-member 32 engages with the stop-face 26 of the body-member 21, the forward end of the said barrel-member is thereby accurately centered with respect to the said body-member.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An anti-recoil device for firearms, including in combination: a body-member having a bore therethrough and designed and adapted to be secured at one end to the forward end of the barrel of a firearm, the said body-member having a rearwardly-facing stop-abutment situated for engagement by a portion of the below-described reciprocating supplemental barrel-member, the said body-member also having a gas-vent means leading outwardly from its bore to its exterior; a tubular supplemental barrel-member mounted for axial reciprocation in the bore of the said body-member and having a rearward position therein and a forward position in which it en-

gages with the rearwardly-facing stop-means of the said body-member, the said supplemental barrel-member being provided with vent-closing means positioned to close the gas-vent means in the said body-member when the said supplemental barrel-member is in its rearward position in the said body-member and to uncover the said gas-vent means when the supplemental barrel-member is in its forward position, the said supplemental barrel-member having an axial bore of uninterrupted substantially-cylindrical form from end-to-end and having the rear end of the said bore closely corresponding in diameter to the diameter of the bore of the said barrel, the said supplemental barrel-member and the said body-member being constructed and arranged to cause the rear end of the said supplemental barrel-member to engage directly with the forward end of the said barrel under the tension of the hereinafter-mentioned yielding-means, to thereby guard against the lateral dispersion of shot intermediate the front end of the said barrel and the rear end of the said supplemental barrel-member; and yielding-means normally holding the said barrel-member in its rearward position in the said body-member.

2. An anti-recoil device for firearms, including in combination: a body-member having a bore therethrough and designed and adapted to be secured at its inner end to the forward end of the barrel of a firearm, the said body-member having adjacent its outer end an inwardly-extending lip-portion formed with a rearwardly-facing substantially-annular stop-abutment, the said body-member also having gas-vent means leading outwardly from its bore to its exterior; a tubular supplemental barrel-member mounted for axial reciprocation in the bore of the said body-member and having a rearward position therein in which it seats directly against the front end of the said barrel and a forward position in which a substantially-annular portion of the barrel-member engages with the rearwardly-facing stop-abutment of the said body-member, the said supplemental barrel-member being provided with vent-closing means positioned to close the gas-vent means in the said body-member when the said supplemental barrel-member is in its rearward position in the said body-member and to uncover the said gas-vent means when the supplemental barrel-member is in its forward position; and yielding-means normally holding the said barrel-member in its rearward position in the said body-member.

3. An anti-recoil device for firearms, including in combination: a body-member having a bore therethrough and designed and adapted to be secured at its inner end to the forward end of the barrel of a firearm, the said body-member having adjacent its outer end an inwardly-extending lip-portion formed with a rearwardly-facing substantially-annular stop-abutment, the said body-member also having a series of gas-vent ports displaced one from another in a direction circumferentially of the said body-member and leading outwardly from its bore to its exterior; a tubular supplemental barrel-member mounted for axial reciprocation in the bore of the said body-member and having a rearward position therein in which it seats directly against the front end of the said barrel and a forward position in which a substantially-annular portion of the barrel-member engages with the rearwardly-facing stop-abutment of the said body-member, the said supplemental barrel-member

being provided with port-closing means positioned to close the series of gas-vent ports in the said body-member when the said supplemental barrel-member is in its rearward position in the said body-member and to uncover the said series of gas-vent ports when the supplemental barrel-member is in its forward position; and yielding-means normally holding the said barrel-member in its rearward position in the said body-member.

4. An anti-recoil device for firearms, including in combination: a body-member having a bore therethrough and designed and adapted to be secured at its inner end to the forward end of the barrel of a firearm, the said body-member being provided at its outer end with a mouth-opening smaller in diameter than the said bore and having a rearwardly-facing substantially-annular stop-abutment around the said mouth-opening, the said body-member also having gas-vent means located adjacent its inner end and leading outwardly from its said bore to its exterior; a tubular supplemental barrel-member mounted for axial reciprocation in the bore of the said body-member and having a rearward position in the said bore and a forward position in which a forward portion of the said supplemental barrel-member engages with the substantially-annular rearwardly-facing stop-abutment around the mouth-opening of the said body-member, the said supplemental barrel-member being provided adjacent its inner end with vent-closing means positioned to close the gas-vent means in the inner portion of the said body-member when the said barrel-member is in its rearward position and to uncover the said gas-vent means when the said barrel-member is in its forward position, the said barrel-member having a forwardly-facing spring-seat on its exterior; and a helical spring substantially coaxially located in the bore of the said body-member and having its outer end surrounding the mouth-opening and stop-seat in the said body-member, the said spring having its inner end seated against the forwardly-facing spring-seat on the exterior of the said supplemental barrel-member, the said helical spring acting to normally hold the said barrel-member in its rearward position in the said body-member.

5. The combination of a firearm-barrel with an anti-recoil device which comprises: a body-member having a bore therethrough and rigidly secured at its rear end to the forward end of the said barrel, the said body-member having gas-vent means leading outwardly from its bore to its exterior; a tubular supplemental barrel-member mounted for lengthwise reciprocation in the bore of the said body-member in axial alignment with the bore of the said barrel, the said barrel-member having a rearward position in the bore of the said body-member in which its rear end seats against the forward end of the said barrel, the said barrel-member also having a forward position in the bore of the said body-member, the said supplemental barrel-member being provided with vent-closing means positioned to close the gas-vent means in the said body-member when the said supplemental barrel-member is in its rearward position in the said body-member and to uncover the said gas-vent means when the said supplemental barrel-member is in its forward position; stop-means limiting the forward movement of the said supplemental barrel-member in the bore of the said body-member; and yielding-means normally

holding the said barrel-member in its rearward position to seat its inner end against the forward end of the said barrel and to cause its vent-closing means to close the gas-vent means in the said body-member.

6. The combination of a firearm-barrel with an anti-recoil device which comprises: a body-member having a bore therethrough and rigidly secured at its rear end to the forward end of the said barrel, the said body-member having a series of gas-vent ports displaced one from another in a direction circumferentially of the said body-member and leading outwardly from its bore to its exterior; a tubular supplemental barrel-member mounted for lengthwise reciprocation in the bore of the said body-member in axial alignment with the bore of the said barrel, the said barrel-member having a rearward position in the bore of the said body-member in which its rear end seats against the forward end of the said barrel, the said barrel-member also having a forward position in the bore of the said body-member, the said supplemental barrel-member being provided with port-closing means positioned to close the gas-vent ports in the said body-member when the said supplemental barrel-member is in its rearward position in the said body-member and to uncover the said gas-vent ports when the said supplemental barrel-member is in its forward position; stop-means limiting the forward movement of the said supplemental barrel-member in the bore of the said body-member; and yielding-means normally holding the said barrel-member in its rearward position to seat its inner end against the forward end of the said barrel and to cause its port-closing means to close the gas-vent ports in the said body-member.

7. The combination of a firearm-barrel with an anti-recoil device which comprises: a body-member having a bore therethrough and rigidly secured at its rear end to the forward end of the said barrel, the said body-member being provided at its forward end with a mouth-opening smaller in diameter than the said bore and having a rearwardly-facing substantially-annular stop-abutment around the said mouth-opening, the said body-member also having gas-vent means located adjacent its inner end and leading outwardly from its said bore to its exterior; a tubular supplemental barrel-member mounted for lengthwise reciprocation in the bore of the said body-member in axial alignment with the bore of the said barrel, the said barrel-member having a rearward position in which its rear end seats against the forward end of the said barrel, the said barrel-member also having a forward position in the said body-member in which a forward end of the supplemental barrel-member seats against the rearwardly-facing stop-abutment around the mouth-opening of the said body-member, the said supplemental barrel-member being provided adjacent its rear end with vent-closing means positioned to close the gas-vent means in the inner portion of the said body-member when the said supplemental barrel-member is in its rearward position and to uncover the said gas-vent means when the said supplemental barrel-member is in its forward position, the said barrel-member having a forwardly-facing spring-seat on its exterior; a helical spring substantially coaxially located in the bore of the said body-member and having its forward end surrounding the mouth-opening and stop-seat in the said body-member, the said spring having its rear

end seated against the forwardly-facing spring-abutment on the exterior of the said supplemental barrel-member, the said helical spring acting to normally hold the said supplemental barrel-member in its rearward position to seat its inner end against the forward end of the said barrel and to cause its vent-closing means to close the gas-vent means in the said body-member.

8. An anti-recoil device for firearms, including in combination: a body-member having a bore therethrough and designed and adapted to be secured at its inner end to the forward end of the barrel of a firearm, the said body-member having gas-vent means leading outwardly from its bore to its exterior and also having air-vent means located forwardly of the said gas-vent means; a tubular supplemental barrel-member mounted for axial reciprocation in the bore of the said body member and having a rearward position and a forward position therein, the said supplemental barrel-member being provided with vent-closing means positioned to close the gas-vent means in the said body-member when the said supplemental barrel-member is in its rearward position in the said body-member and to uncover the said gas-vent means when the supplemental barrel-member is in its forward position; means for limiting the forward movement of the said supplemental barrel-member in

the said body-member; and yielding-means normally holding the said barrel-member in its rearward position in the said body-member.

9. An anti-recoil device for firearms, including in combination: a body-member having a bore therethrough and designed and adapted to be secured at its inner end to the forward end of the barrel of a firearm, the said body-member having gas-vent means leading outwardly from its bore to its exterior and being formed with conically-contoured stop-means; a tubular supplemental barrel-member mounted for axial reciprocation in the bore of the said body-member and having a rearward position and a forward position therein, the said supplemental barrel-member being provided with vent-closing means positioned to close the gas-vent means in the said body-member when the said supplemental barrel-member is in its rearward position in the said body-member and to uncover the said gas-vent means when the supplemental barrel-member is in its forward position, the said barrel-member being formed with conically-contoured stop-means engaging the similar stop-means of the said body-member when the said barrel-member is in its forward position; and yielding-means normally holding the said barrel-member in its rearward position in the said body-member.

RUSSELL M. CATRON.
